UNITED STATES PATENT OFFICE.

ALBERT F. LICKTEIG, OF NEW HAVEN, CONNECTICUT, ASSIGNOR TO ADAM F. LICKTEIG, OF NEW HAVEN, CONNECTICUT.

DOORLOCK.

Application filed March 25, 1925. Serial No. 18,081.

To all whom it may concern:

Be it known that I, ALBERT F. LICKTEIG, a citizen of the United States, residing at New Haven, county of New Haven, State 5 of Connecticut, have invented a new and useful Doorlock, of which the following is a specification.

This invention relates to a door lock, and although the disclosure has particular reference to an automobile door lock, my improved lock is by no means limited to use with automobile doors, but is adapted for general application.

It is an object of the invention to provide an improved lock which will be simple in construction and so may be manufactured at low cost, will be reliable in operation and not easily gotten out of order.

It is also an object of the invention to provide a lock which may be locked from the inside of the door or the automobile by a slight movement of the bolt operating lever or handle, and which when locked will prevent the bolt from accidentally withdrawing from the strike plate or keeper under vibration and thus allow accidental release of the door.

It is a further object of the invention to provide a lock, which, although it may be locked from the inside by movement of the operating handle, may be locked or unlocked from the outside by means of a key.

With the foregoing and other objects in view, I have devised the construction illustrated in the accompanying drawings forming a part of this specification, similar reference characters being employed throughout the various figures to indicate corresponding elements. In these drawings,

Fig. 1 is a side elevation of the lock mechanism in the locked position looking toward the outside of the door and with the outer plate of the casing removed.

Fig. 2 is a similar view showing the position of the elements with the bolt retracted.

Fig. 3 is a transverse section substantially on line 3—3 of Fig. 1.

Fig. 4 is a top plan view looking down on Fig. 1.

Fig. 5 is a detail section substantially on line 5—5 of Fig. 2.

Fig. 5^a is a detail section substantially on line 5^a—5^a of Fig. 1.

Fig. 6 is a detail elevation showing the operation of the key control cam.

Fig. 7 is a similar view showing the operation of retracting the bolt by a handle on the outside of the door.

Fig. 8 is a view similar to Fig. 1 showing a slightly different construction.

Fig. 9 is a view similar to Fig. 8 showing the elements in the position they occupy when the bolt is retracted, and

Fig. 10 is a transverse section substantially on line 10—10 of Fig. 8.

Generally speaking my improved lock comprises a movable bolt normally held in securing position by a spring, a pivoted operating lever connected to the bolt, a movable actuating member which has lost motion connection with the lever, and which lever and actuating member have coacting shoulders which in one position of the actuating member lock the lever against movement, and an operating handle connected to the actuating member for shifting this member to first unlock the lever and then swing the lever to retract the bolt. One form of my invention has further means connected with the operating handle for locking the bolt in the extended or holding position when the handle is in one position.

Referring to Figs. 1 to 7 inclusive, 10 represents a section of a door, as an automobile door, swinging on suitable hinges, not shown, to and from a jamb or one side of the door opening 11. The lock mechanism is mounted in a casing 12 open at one side which is closed by the plate 13, one side of the plate being bent at an angle as shown at 14 and provided with an opening through which the head 15 of the bolt 16 projects, and in which it is slidable. The bearing surface for the head may be increased by bending laterally the portion of the plate at the side of the opening, as shown at 17. The bolt 16 in the present construction is a slidable bolt and carries a laterally projecting pin 18 extending into an elongated slot 19 in the plate 13 and in which it is guided. An operating lever 20 is pivotally mounted in the casing at 21 and this lever engages the pin 18 adjacent its free end, the lever being provided with a curved edge 22 which engages this pin. This lever carries a laterally projecting pin or stud 23 which extends into an elongated slot 24 in a movable actuated member 25. In the present construction the member 25

is slidable on the top of the bolt. Mounted to turn in the casing and extending vertically therein is a shaft 26 having an operating handle 27 connected thereto. The shaft is provided with a laterally extending arm 28 having a lug 29 which may in a certain position of the shaft enter a recess 30 in the upper edge of the bolt 16 and lock the bolt against movement. This is the position shown in full lines in Fig. 1. It will be apparent that the lug 29 when in this position is in the path of movement of the shoulder at the outer side of the recess 30 and will, therefore, prevent inward or retracting movement of the bolt, but as the recess is open on the side of the bolt this lug may move from the recess when the shaft is turned to the dotted line position in Fig. 4. The actuating slide or member 25 has a recess 31 which is adapted to receive and straddle the arm 28 so that this member may be shifted by the swinging movement of the arm as the shaft is turned about its axis. The notch or recess 31 is, however, of a greater width than the thickness of the arm to allow certain lost motion between the elements for a purpose presently to be described. The shaft 26 is provided with a pair of flats 32 and 33 on different sides thereof which are engaged by a spring 34 to yieldingly retain this shaft in either the full line or dotted line position shown in Fig. 4. The bolt 16 is normally held in its extended or holding position shown in Fig. 1 with its head 15 projecting through an opening in the strike plate 35 carried by the jamb 11 as is the usual operation by means of a spring 36. This spring may be of any desired or preferred construction but is shown as a convolute spring having a free end 37 engaging the pin 18 carried by the bolt on the opposite side from the engagement of the operating lever 20 therewith. At its other end it is secured to the casing by any means desired.

I also prefer to use another spring 38 which is connected to the operating lever 20 and tends to swing it clockwise as viewed in Figs. 1 and 2, although this spring is not absolutely necessary, and the pivot 21 for this lever is so located that should this spring 38 fail or become broken the lever will of its own weight tend to move to the position shown in Fig. 1. The lever 20 and the actuating member 25 are provided with coacting means which will lock the lever against movement when the actuating member 25 is in a certain position. For this purpose the lever is provided with a lug 39 having a shoulder 40, and the actuating member 25 is bent backwardly as shown at 41 to form a rib having a shoulder 42, which, when the lever and actuating member are in the position shown in full lines in Fig. 1,

will lie over the shoulder 40 carried by the lever and will prevent this lever swinging backwardly or to the right as viewed in Fig. 1.

There is also provided a cam or follower 43 which is rotatably mounted in the casing and has a square opening 44 to receive the usual square spindle or a latch operating handle 45 (Fig. 7) on the outside of the door. This cam or follower is mounted so that the projecting ends thereof will engage the edge of the operating lever 20 and swing the same, as shown in Fig. 7, on its pivot to retract the bolt when the bolt is unlocked.

I also provide key control means for locking or unlocking the bolt. For this purpose I have shown the usual cam 46 connected to the ordinary type of pin tumbler cylinder 47 which is accessible from the outside of the door for operation by the usual key 48. The actuating member 25 is provided with a recess 49 in one edge thereof to coact with this cam 46 to shift the actuating member and lock or unlock the bolt.

The operation of this lock is as follows: When the door is closed and the handle 27 is in the full line position shown in Figs. 1 and 4 the bolt is extended into engagement with the strike plate or keeper, as shown in full lines, and the lug 29 on the arm 28 carried by the shaft 26 is seated in the notch or recess 30 and will lock the bolt in this position so that it cannot be retracted, and the handle and shaft will be held in this position by the spring 34 engaging the flat 32. If it is now desired to unlock the door from the inside the handle 27 is shifted inwardly a short distance to the dotted line position shown in Fig. 4. This movement will withdraw the lug 29 from the recess 30 in the bolt and will thus unlock the bolt and allow it to move backwardly either by slamming the door or by operation of the lever 20. This movement of the handle by swinging the arm 28 shifts the actuated member 25 to the right as viewed in Fig. 1 to the dotted line position. This movement is sufficient to move the shoulder 42 carried by the actuating member away from and out of the path of movement of the shoulder 40 carried by the operating lever, and will thus unlock this lever. It will also bring the left hand end of the slot 24 into engagement with the pin 23 carried by the lever 20. It will thus be seen that the bolt can now be retracted by swinging the cam or follower 43 by means of the handle 45 on the outside of the door, as shown in Fig. 7, if desired. The shaft 20 and the handle 27 will be held in this position by the spring 34 engaging the flat 33.

If the handle 27 and shaft 26 are swung still further in the same direction, as to the dot and dash line position shown in Fig. 4,

the arm 28 will shift the actuating member 25 still further to the right, and the end of the slot 24 engaging the pin or stud 23 on the lever 20 will swing this lever to the right and by engagement of the lever with the pin 18 on the bolt 16 will retract the bolt and allow the door to be opened. The elements are now in the positions shown in Fig. 2. As soon as the handle is released the springs 36 and 38 will return the handle to the dotted line position shown in Fig. 4, the actuating member to the dotted line position shown in Fig. 3, and the bolt and operating lever to the full line position shown in Fig. 1. As pointed out above, when the handle is in this position the bolt may be moved backwardly and the door may be closed by slamming if desired. After the door is closed the operator may lock it from the inside by merely swinging the handle 27 from the dotted line position shown in Fig. 4 to the full line position. Thus the door may be locked from the inside without the use of a separate catch or key but by means of the operating handle. The bolt may be locked from the outside by means of a key 48 by rotating the cam 46 to engage the left side of the recess 49 to shift the actuating member 25 from the dotted line position (Fig. 1) to the full line position. This will bring the rib 41 carried by the actuating member over the lug 39 carried by the operating lever and will lock the lever so that it cannot be swung backwardly by the handle 45 to retract the bolt. By rotating the cam 46 in the opposite direction it will engage the right hand side of the recess 49 and shift the actuating member 25 to the right to the dotted line position in Fig. 1 and move the rib 41 away from the lug 39 and unlock the operating lever 20. The bolt may now be retracted by turning the handle 45.

It will be apparent from the foregoing description that the bolt is not operated direct from the shaft 26, but that the shaft shifts the actuating member 25 which swings the operating lever 20 and this lever retracts the bolt. There is, however, a direct acting locking means for the bolt carried by the shaft, and thus, although the bolt may be retracted by the shaft through the handle 27, it may also be locked and unlocked by a small movement of this handle. There is also a positive lock between the actuating member and the operating lever which may be controlled by the handle 27 or may be controlled by the key controlled cam. The positive lock for the bolt is important in automobile use, and the feature of locking by means of the operating handle gives a very quick and simple operated means of locking the door from the inside without the necessity of manipulating a separate catch or lock and without using the

key. The operator, therefore, in a closed car when leaving the car may lock the door on the opposite side from the side on which he leaves the car by merely pushing outwardly on the handle 27. This is also a safety feature, because, when the handle is in this position there is a positive lock for the bolt, so that should some one be leaning against the door the jar could not cause the bolt to move backwardly and the pressure on the door hold it in this position until another slight backward movement caused by a jar and so on until the bolt is eventually fully retracted and allow the door to open, as has actually happened in the old types of constructions. It will be apparent in this construction there is no possibility of the bolt accidentally becoming retracted to release the door. When the lock is used in house doors this positive locking feature will prevent the bolt being retracted by the insertion of a thin strip of metal between the edge of the door and the jamb. The side of the recess which engages the lug 29 may be inclined at the rear portion thereof as shown at 30° to engage the lug 29 so that an attempt to force the bolt backwardly will tend to keep the lug in the recess and so will not turn the shaft to remove the lug from the recess.

In Figs. 8, 9 and 10 I have shown a slightly different construction. In this construction, instead of a rotary shaft 26 for operating bolt 16, I employ a lever 50 pivoted in the casing at 51 so as to swing in the plane of the door. The bolt is operated by the same operating lever 20, but the actuating member 52 is of a somewhat different construction than the actuating member 25 in the first construction. This actuating member has an elongated slot 53 to receive the pin or stud 23 carried by the lever 20, but it has an arm 54 which is pivotally connected with the lever 50 by any suitable means as a screw stud 55. The actuating member 52 has an upright rib 56 corresponding to the rib 41 in the first form which coacts with the lug 39 on the lever 20 to lock this lever against movement the same as in the first form. The actuating member 52 is also provided with a recess 57 for coaction with the cam 46 of the key cylinder whereby this actuating member may be shifted to lock or unlock the lever.

It will be noted that in this form there is no direct locking means from the lever 50 to the bolt 16 corresponding to the locking means 29 and 30 in the first form, and therefore, the bolt carries a second stud or pin 58 on the opposite side of the lever from the pin 18. It will, therefore, be seen that when the actuating member 52 is in the full line position of Fig. 8 the rib 56 will be in the path of movement of the lug 39 on the lever 20 to prevent backward movement

of this lever, and therefore, the bolt cannot be retracted because the pin 58 will engage the forward edge of the lever and prevent this backward movement. By moving 5 the lever 50 to the dotted line position shown in Fig. 8 the actuating member 52 will be drawn to the dotted line position carrying the rib 56 away from the lug 39 and unlock the lever 20 so that the bolt may be 10 retracted. This movement to the dotted line position will take place without shifting the lever 20 because of the elongated slot 53, but continued movement of the lever 50 from the dotted line position in Fig. 8 15 to the position shown in Fig. 9 will swing the lever 20 and retract the bolt as indicated. When the bolt is unlocked it may be swung to retract the bolt by means of the cam or follower 43 operated by a handle on the 20 outside of the door, the same as in the first form, and the actuating member 52 may be shifted to lock or unlock the lever 20, and therefore, the bolt 16, by means of a key from the outside of the door operating 25 through the pin tumbler cylinder 47 and the cam 46, the same as in the first form. It will be noted that in this form the bolt is locked against retraction by a slight movement of the operating lever 50 the 30 same as in the first form, and that it is first unlocked by a slight movement of this lever in the opposite direction and may then be retracted by a further movement in the same direction, the same as in the first 35 form. This locking means in this form will also prevent the bolt becoming accidentally released in operation, and the lever 50 may be yieldingly held in either the full line or dotted line positions in Fig. 8 by a spring 40 60 engaging recesses 61 in the side of the lever.

Having thus set forth the nature of my invention, what I claim is:

1. In a lock, a movable bolt, a lever having connection with the bolt for operating the same, a movable actuating member having a lost motion connection with the lever, said lever and actuating member being provided with coacting means to prevent movement of the lever when the actuating member is in a given position, and means for shifting the actuating member to retract the bolt.
2. In a lock, a movable bolt, an operating member for the bolt, a movable actuating member having operative connection with the operating member, said members being provided with coacting means to prevent movement of the operating member when the actuating member is in a given position, and means for moving the actuating member to unlock the operating member and to retract the bolt.
3. In a lock, a movable bolt, an operating member for the bolt, a movable actuating

member having operative connection with the operating member, said members being provided with coacting means to prevent movement of the operating member when the actuating member is in a given position, 70 and a key controlled means for shifting the actuating member to unlock the operating member.

4. In a lock, a movable bolt, a pivoted lever having connection with the bolt for operating the same, a movable actuating member having a lost motion connection with the lever, said lever and actuating member being provided with coacting means to prevent movement of the lever when the actuating member is in a given position, and a key controlled means for shifting the actuating member to unlock the lever.

5. In a lock, a movable bolt, an operating member for the bolt, a movable actuating member having operative connection with the operating member, a rotatable shaft provided with a laterally extending projection, said bolt being provided with a shoulder to engage said projection to prevent retraction 90 of the bolt when the shaft is in one position, said projection being arranged to move from said shoulder on operation of the shaft, and an operative connection from the shaft to the actuating member for retracting the 95 bolt on further operation of the shaft.

6. In a lock, a movable bolt having a recess therein, a rotatable shaft having a laterally extending arm having a projection adapted in one position of the shaft to enter 100 said recess and prevent retraction of the bolt, said projection being arranged to move from said recess on operation of the shaft, a pivoted lever having operative connection with the bolt, and an actuating member 105 connected to the lever and provided with a recess to receive said arm to shift the actuating member to retract the bolt on further movement of the shaft.

7. In a lock, a movable bolt, an operating member for the bolt, a movable actuating member having operative connection with the operating member, said members being provided with coacting means to prevent movement of the operating member 115 when the actuating member is in a given position, a rotatable shaft provided with a laterally extending projection, said bolt being provided with a shoulder to engage said projection to prevent retraction of the bolt 120 when the shaft is in one position, said projection being arranged to move from said shoulder on operation of the shaft, and an operative connection from the shaft to the actuating member to shift said member to 125 unlock the operating member on said movement of the shaft and to retract the bolt on further movement of the shaft.

8. In a lock, a movable bolt having a recess therein, a rotatable shaft having a lat-

- erally extending arm having a projection adapted in one position of the shaft to enter said recess and prevent retraction of the bolt, said projection being arranged to move 5 from said recess on operation of the shaft, a pivoted lever having operative connection with the bolt, an actuating member connected to the lever, said lever and member being provided with coacting means to prevent 10 movement of the lever when the actuating member is in a given position, said actuating member being provided with a recess to receive said arm to shift the actuating member and unlock the lever on said above mentioned movement of the shaft and to retract 15 the bolt on further movement of the shaft.
9. In a lock, a movable bolt, an operating member for the bolt, a movable actuating member having operative connection with 20 the operating member, a rotatable shaft provided with a laterally extending projection, said bolt being provided with a shoulder to engage said projection to prevent retraction of the bolt when the shaft is in one position, said projection being arranged to move 25 from said shoulder on operation of the shaft, an operative connection from the shaft to the actuating member for retracting the bolt on further operation of the shaft, and 30 means for yieldably holding the shaft in either the first or second position.
10. In a lock, a movable bolt having a recess therein, a rotatable shaft having a laterally extending arm having a projection 35 adapted in one position of the shaft to enter said recess and prevent retraction of the bolt, said projection being arranged to move from said recess on operation of the shaft, a pivoted lever having operative connection 40 with the bolt, an actuating member connected to the lever and provided with a recess to receive said arm to shift the actuating member to retract the bolt on further movement of the shaft, and yieldable means 45 for holding the shaft in the locking and unlocked positions.
11. In a lock, a slidable bolt having an open sided recess in one side thereof, a rotatable shaft having a laterally projecting arm 50 adapted to enter said recess in one position of the shaft and lock the bolt against movement, a pivoted operating lever connected to the bolt, a pin carried by said lever, and a slidable actuating member having an elongated slot to receive said pin and also provided with a recess to receive 55 the said arm to shift the actuating member on rotation of the shaft, said elements being arranged to cause movement of the lug from the recess in the bolt to unlock the same on the first movement of the shaft and then to swing the operating lever to retract the bolt.
12. In a lock, a slidable bolt having an open sided recess in one side thereof, a rotatable shaft having a laterally projecting arm 60 adapted to enter said recess in one position of the shaft and lock the bolt against movement, a pivoted operating lever connected to the bolt, a pin carried by said lever, and a slidable actuating member having an elongated slot to receive said pin and also provided with a recess to receive 65 the said arm to shift the actuating member on rotation of the shaft, said elements being arranged to cause movement of the lug from the recess in the bolt to unlock the same on the first movement of the shaft and then to swing the operating lever to retract the bolt.
13. In a lock, a slidable bolt having an open sided recess in one side thereof, a rotatable shaft having a laterally projecting arm 70 adapted to enter said recess in one position of the shaft and lock the bolt against movement, a pivoted operating lever connected to the bolt, a pin carried by said lever, and a slidable actuating member having an elongated slot to receive said pin and also provided with a recess to receive the said arm to shift the actuating member on rotation of the shaft, said lever and actuating member being provided with coacting shoulders to prevent movement of the lever when the shaft is in locking position, said elements being arranged to cause movement of the lug from the recess in the bolt and 75 to shift the actuating member to unlock the bolt and the lever on the first movement of the shaft and then to swing the operating lever to retract the bolt.
14. In a lock, a slidable bolt having an open sided recess in one side thereof, a rotatable shaft having a laterally projecting arm 80 adapted to enter said recess in one position of the shaft and lock the bolt against movement, a pivoted operating lever connected to the bolt, a pin carried by said lever, and a slidable actuating member having an elongated slot to receive said pin and also provided with a recess to receive the said arm to shift the actuating member on rotation of the shaft, said lever and actuating member being provided with coacting shoulders to prevent movement of the lever when the shaft is in locking position, said elements being arranged to cause movement of the lug from the recess in the bolt and 85 to shift the actuating member to unlock the bolt and the lever on the first movement of the shaft and then to swing the operating lever to retract the bolt.
15. In a lock, a movable bolt, a pivoted lever having connection with the bolt for operating the same, a movable actuating member connected to the lever, means for shifting the actuating member to retract the bolt, a rotatable cam engaging the lever, and a handle for rotating the cam to swing 90 the lever and retract the bolt.
16. In a lock, a movable bolt, a pivoted lever having connection with the bolt for operating the same, a movable actuating member having a lost motion connection with the lever, said lever and actuating member being provided with coacting means to prevent movement of the lever when the actuating member is in a given position, means for shifting the actuating member to unlock the lever and retract the bolt, a cam engaging the lever, and a handle for operating the cam to retract the bolt.

In testimony whereof I affix my signature.

ALBERT F. LICKTEIG.
